UNITED STATES PATENT OFFICE.

JAMES FITZSIMMONS, OF NEW ORLEANS, LOUISIANA, ASSIGNOR OF ONE-HALF TO H. W. ROELING, OF NEW ORLEANS, LOUISIANA.

CARDBOARD BOX.

1,321,727.

Specification of Letters Patent. Patented Nov. 11, 1919.

Application filed February 18, 1918. Serial No. 217,889.

To all whom it may concern:

Be it known that I, JAMES FITZSIMMONS, a citizen of the United States, residing at New Orleans, in the parish of Orleans and 5 State of Louisiana, have invented certain new and useful Improvements in Cardboard Boxes; and I do declare the following to be a full, clear, and exact description of the invention, such as will enable others skilled in 10 the art to which it appertains to make and use the same.

One object of my invention is to provide a strong and durable box which may be formed of a single sheet of cardboard with 15 little waste.

A further object is to provide a box having a flanged cover and a novel rear corner construction whereby the end flanges are prevented from springing away from the 20 box.

Another object is to devise an extremely strong front corner construction for both the box proper and its hinged cover.

A still further object is to provide a novel 25 fastening means for the cover.

With the foregoing general objects in view, the invention resides in the novel features of construction and unique combinations of parts to be hereinafter fully described and claimed, the descriptive matter 30 being supplemented by the accompanying drawings which form a part of this specification and in which:

Figure 1 is a plan view of the cardboard 35 blank from which the box is constructed;

Fig. 2 is a perspective view of the box with its cover open;

Fig. 3 is a similar view of the box in closed position;

Fig. 4 is a transverse section on the plane indicated by the line 4—4 of Fig. 3; and

Fig. 5 is a detail horizontal section on the planes of the line 5—5 of Fig. 4.

Since the construction of the improved 45 box can be better understood by first describing the blank from which it is formed, this course will be followed; and to this end, reference may be had more particularly to Fig. 1. The numeral 1 designates a rectangular bottom having a front side 2, a rear side 3, and two ends 4 formed integrally with its edges. Triangular front flaps 5 are joined integrally to the ends of the front side 2 and are provided with flap extensions 6 50 extending laterally from the outer edge of

said side, the free outer ends of said extensions having T-shaped tongues 7 adapted for passage through short longitudinal slots 8 in the front portions of the ends 4 as will be hereinafter described. The ends of the 60 rear side 3 are provided with integral rectangular flaps 9 having T-shaped tongues 10 on their outer ends for passage through short transverse slots 11 in the rear portions of the ends 4. 65

A rectangular top 12 is integral with the upper edge of the rear side 3, the front edge of said top having a front flange 13 while the ends of said top are provided with end flanges 14. Triangular flaps 15 are formed 70 integrally with the flange 13 and are provided with flap extensions 16 whose free ends are equipped with T-shaped tongues 17 for passage through short longitudinal slots 18 in the front portions of the end flanges 75 14. The free outer edges of the flanges 14 are each formed with a substantially V-shaped notch 19, said notches being located near the rear ends of these flanges and serving to clear the tongues 10 when the box is 80 assembled.

A fastening tongue 20 is integral with the free edge of the front side 2 and co-operates with a pair of central longitudinally disposed slots 21 in the front flange 13. The 85 entire blank above described is stamped from a single rectangular sheet of cardboard and it will be obvious by reference to Fig. 1 that very little waste occurs.

In assembling, or rather in folding the 90 box for use, the sides 2 and 3 and the ends 4 are folded upwardly, the flaps 9 being folded into contact with the outer sides of the ends 4 as shown clearly in Fig. 2, with their tongues 10 passing through the slots 11. 95 The flaps 5 are folded into contact with the inner sides of the ends 4 and the flap extensions 6 are folded over the upper edges of said ends into contact with the outer sides of the latter, the tongues 7 being passed 100 inwardly through the slots 8. By this arrangement, an extremely strong and durable front corner construction is provided. The end flanges 14 and the front flange 13 of the top 12 are folded into right angular relation with said top, and the flaps 15 are folded against the inner sides of said end flanges 14. The flap extensions 16 are then folded around the edges of said side flanges 105 into contact with the outer sides of the lat- 110

ter and the tongues 17 are passed inwardly through the slots 18. This corner construction is identical with that at the front corners of the box proper and possesses the 5 same advantages.

When the top 12 is folded downwardly, the rear ends of the side flanges 14 are received between the ends 4 and the rear flaps 9 so that springing of said flanges away 10 from the box is prevented. The notches 19 in the flanges 14 are provided to clear the tongues 10 as is shown clearly in full lines in Fig. 3 and in dotted lines in Fig. 4. To fasten the cover in closed position, the 15 tongue 20 is passed outwardly through the uppermost slot 21 of the front flange 13 (see Fig. 4) and is then passed inwardly through the lower slot, its free end being received between the flange in question and the front 20 side 2 of the box. This forms a strong and effective fastening means and if required a suitable seal or sticker may be applied over the tongue to prevent tampering therewith.

From the foregoing, taken in connection 25 with the accompanying drawings, it will be obvious that although my invention is of extremely simple and inexpensive nature, it will be highly efficient and durable, particu- 30 lar emphasis being laid upon the reception of the end flanges 14 between the flaps 9 and the ends 4, upon the tongues 7 and flap extensions 6 on the flaps 5, and upon the fastening tongue 20 in connection with the 35 slots 21. Since probably the best results are obtained from the exact features shown and

described, these features are by preference employed, but within the scope of the invention as claimed, numerous minor changes may well be made.

I claim:

A cardboard box formed of a single blank and comprising a rectangular bottom, ends, a back and a front bent up from said bottom, a top integral with said back and bent to form ends and a front, both fronts having 45 triangular flaps bent inwardly into contact with the inner sides of said ends, said flaps having edges inclining to the free edges of said ends and the latter having slots spaced from said inclined edges, rectangular exten- 50 sions on said flaps folded around the free edges of said ends onto the outer sides of the latter and having T shaped tongues inserted through said slots, rectangular rear flaps on the ends of said back folded onto 55 the outer sides of the adjacent ends and having T shaped tongues, said last named ends having slots through which said tongues are inserted; the lower edges of the ends carried by said top having angular notches forming 60 triangular portions for reception between said rear flaps and the ends bent up from said bottom.

In testimony whereof I have hereunto set my hand in the presence of two subscribing 65 witnesses.

JAMES FITZSIMMONS.
